UNITED STATES PATENT OFFICE.

EDMUND A. SCHADE, OF NEW BRITAIN, CONNECTICUT, ASSIGNOR TO THE STANLEY WORKS, OF NEW BRITAIN, CONNECTICUT, A CORPORATION OF CONNECTICUT.

PLANE.

Application filed December 18, 1925. Serial No. 76,317.

This invention relates to carpenters' planes, and has as its aim to provide a plane with the improved means for adjusting the cutter relative to the plane body, and which means is particularly characterized by its simplicity in construction, its economy in manufacture, and the effectiveness with which it performs its functions.

In accordance with the present invention, the means for adjusting the cutter is mounted on the cap or lever which is clamped against the top of the cutter so that the adjusting means is readily accessible, the parts may be easily assembled, and the cutter may be properly supported on the plane body at a relatively low angle, if desired.

Other objects will be in part obvious and in part pointed out more in detail hereinafter.

The invention accordingly consists in the features of construction, combination of elements and arrangement of parts which will be exemplified in the construction hereinafter set forth, and the scope of the application of which will be indicated in the appended claim.

In the accompanying drawings, wherein I have shown, for illustrative purposes, one of the many embodiments which the present invention may take:

Figure 1 is a longitudinal sectional view through the plane;

Fig. 2 is a top plan view of the cap on which the adjusting means is mounted;

Fig. 3 is a top view of a slide adapted to be adjustably clamped to the cutter; and

Fig. 4 is a view of the cutter or "plane iron."

It is, of course, understood that the body of the plane may be of any suitable or standard construction and shape. By way of illustration, the plane body is shown in the drawings as having a sole 10, side flanges 11, an adjustable shoe 12 between which and the forward edge of the sole is a slot or throat 13, and a frog or seat 14 adjacent the throat. The plane body also has one or more pillars 15 which form a seat for the cutter rearwardly of the frog 14. At the forward end of the plane is the usual knob 16 and at the rear end a handle 17. The cutter or plane bit, designated by the numeral 20, has a central longitudinally-extending slot 21 adapted to accommodate an integral internally threaded boss 18 arising

from the sole 10. The cutter is clamped in place on the seat provided by the frog 14 and the pillars 15 by a cap or lever 25 and a clamping or cap screw 26. The clamping lever has the usual key-slot 27, the larger portion of which is of sufficient diameter to permit the head of the screw 26 to pass therethrough and the edge of the smaller portion of which constitutes a seat for the inner tapered end of the head of the screw. 65

In accordance with the present invention, there is provided on the cap an adjustable member with means for adjusting the same, the adjustable member having cooperative engagement with the cutter so that, when the member is adjusted, the cutter is moved rearwardly or forwardly, as the case may be, to change the extent to which the cutting edge of the cutter extends into the throat 13. In the present illustrative disclosure, the adjustable member is in the form of a lever 30 extending through an opening 31 in the cap and pivoted in this opening on a transverse pin 32. The upper end of the lever is in the form of a yoke 33, and the yoke arms engage in a circumferential groove 34 of a nut 35 screwed onto a threaded stud 36 carried by, and extending upwardly from, the cap 25 adjacent its rear end. The lower end of the lever 30 is operatively connected with the cutter so that, when the lever 30 is adjusted in one direction, the cutter is slightly withdrawn, and, when moved in the other direction, the cutter is slightly advanced. In the present 90 illustrative showing, the forward end of this lever extends through a rectangular slot 37 in a slide 38 which is adjustably connected to the cutter. The slide 38 may be clamped in any desired position of adjustment by 95 means of a screw 39 which extends upwardly through a slot 40 in the cutter. The forward end of the slide has a depending lip 41 corresponding in length to the width of, and adapted to engage in, the slot 21 so that the slide is held against rotary movement.

It will be seen that, to adjust the cutter, it is merely necessary to turn the nut 35 in the right direction, and this may be easily done because the nut is in a position where it can be readily gripped. When the nut 35 is turned down on the stud 36, the cutter will be advanced so as to extend further through the slot and, when the nut is turned in such a direction that it moves 110

upwardly, the cutter will be withdrawn. The adjustable slide 38 is provided so that, as the cutter is shortened or worn away by successive sharpening operations, the proper relation between the lever 30 and the cutter may be maintained. In one manner of speaking, the forward and rear edges of the slot 37 provide abutments on the cutter and between which abutments the lower end of the lever 30 is adapted to extend.

It is obvious that my improvements are very simple in construction and arrangement and very effective in operation.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claim is in-

tended to cover all of the generic and specific features of the invention herein described and all statements of the scope of the invention which, as a matter of language, might be said to fall therebetween.

I claim as my invention:

A plane having a body, a cutter adjustably carried thereby and having a longitudinally extending slot, a cap removably clamped to said body and against said cutter, said cap having an opening adjacent its rear end, an adjustable slide having an opening and a lip extending into and engaging the side edges of said slot, a screw for adjustably connecting said slide to said cutter, a lever pivoted in the opening of said cap and having its lower end engaging in the opening of said slide, the upper end of said lever having a fork, a stud carried by said cap, and a nut on said stud having a circumferential groove in which the fork of said lever engages.

EDMUND A. SCHADE.
